ABSTRACT: A guarding apparatus responsive to violation of the security of an area or space, comprising a printed or similar gridlike circuit configuration of conductors, preferably of resistance characteristic, connected to form one or several continuous trigger circuits. The configuration may be in the nature of printed circuit panels arranged to enclose, preferably completely, the desired area of security, as by constituting part of the walls, floor, junction or connector boxes and the like. The circuitry is connected, as by a cable, to an energized electrical detector which may comprise an instrument movement and a bridge, whereby any shorting or breaking of one or more of the printed or similar conductors will result in a response by the instrument movement.

PRINTED-CIRCUIT TYPE SECURITY APPARATUS FOR PROTECTING AREAS

CROSS-REFERENCES TO RELATED APPLICATIONS

1. Copending application of Elwood R. Horwinski, Ser. No. 755,203, filed Aug. 26, 1968, and having common ownership with the present invention.
2. Copending application of Elwood R. Horwinski, Ser. No. 761,725 filed Sept. 23, 1968, and having common ownership with the present invention.

BACKGROUND

This invention relates to electrical security measures for 15 guarding restricted areas or spaces, and more particularly to electrical equipment intended to signal or indicate unauthorized violations or trespassing of such areas.

Heretofore various systems such as light or infrared beams, electric eyes, high or lethal voltage guards and the like have been utilized to safeguard restricted areas, where unauthorized personnel were not desired. These systems have proved to be satisfactory in a number of instances, but drawbacks invariably existed. The high voltage installations constituted a hazard and danger to workers and other authorized personnel in the area. Some prior systems were vulnerable to power failure, others could be defeated too easily by the use of more or less sophisticated equipment in the hands of an unscrupulous person.

SUMMARY

The above disadvantages and drawbacks of prior devices intended to guard restricted areas are obviated by the present invention, and one object is to provide an improved area or space security apparatus adapted to guard both small and large areas, including electrical junction boxes for guard-type cables, which is readily fabricated by existing processes and especially effective and resistant to efforts intended to defeat its purpose. This is accomplished by the provision of a combination of interconnected printed or similar gridlike circuit configurations constituted of crossing insulated conductors which are connected so as to form at least one continuous trigger circuit or preferably a plurality of such circuits, said circuit or circuits being in turn connected to an electrical detection device which will indicate any alteration of the circuit characteristics. The conductor grid is arranged to enclose the space being protected or guarded, as by applying it to wall, ceiling and floor surfaces and the like, or incorporating it in wall and other paneling construction. For such purposes, the conductor grid is fabricated to be essentially flat or planar. Other grid configurations may be utilized, however, to suit particular situations.

Other objects and advantages reside in an improved area security apparatus as above indicated, which lends itself well to both existing and new constructions of buildings, rooms, vaults, safe boxes, junction boxes and the like; a security apparatus which is relatively simple and inexpensive, reliable and foolproof in operation, easily serviced, not subject to malfunctioning because of commercial power failure, wholly safe from the standpoint of fire and explosion hazard, damage to its environment or danger to personnel; and a highly effective security apparatus which is especially flexible in being adapted to a large variety of conditions and applications.

Other features and advantages will hereinafter appear.

In the drawings:

FIG. 1 is a diagrammatic representation of one form of area security device as provided by the invention.

FIG. 2 is a fragmentary section taken on line 2-2 of FIG. 1.

FIG. 3 is a fragmentary section taken on line 3-3 of FIG. 1.

FIG. 4 is a section through a rolled wallpaper having a printed-circuit grid, in accordance with the invention.

FIG. 5 is an edge elevation of a segment of plywood paneling having on one side a printed-circuit grid.

FIG. 6 is a fragmentary section of plaster or wallboard having on one side a printed circuit grid.

FIG. 7 is a schematic circuit diagram of a sensitive detector circuit and control constituting part of another form of the invention.

FIG. 8 is a diagrammatic representation somewhat like that of FIG. 1, but of another embodiment of the invention.

FIG. 9 is a perspective view of a vault or small building lined with printed circuit grids and adapted to be guarded by the apparatus of the invention.

FIG. 10 is a perspective view of a strong box or safe lined with a printed-circuit grid according to the invention.

FIG. 11 shows a junction box lined with the printed circuit grids which are connected to two cable ends.

FIG. 12 is a fragmentary section on the line 12-12 of FIG. 11.

FIG. 13 is a side elevational view of a simple cable construction having inner and outer braids, which is usable with the junction box of FIGS. 11 and 12.

FIG. 14 is an elevation showing a bag or tarpaulin which is lined with printed-circuit elements and connected by a cable to a detector station.

FIG. 15 is a circuit diagram of a simplified electrical detector as provided by the invention.

Referring first to FIG. 1, there is illustrated a bridge circuit designated generally by the numeral 20, having variable resistors 22, 24, 26 and 28 respectively in its four legs, the corner junctions of the bridge being designated 30, 32, 34 and 36. A source of energy or battery 38 is connected between the corner junctions 32, 36 and a galvanometer or equivalent indicating instrument 40 is connected between the corner junctions 30, 34.

In conjunction with the bridge 20, according to the present invention there is provided a novel, space enclosure having trigger circuits, said enclosure comprising an electrical grid formation 42 constituted of sets of parallel, printed-circuit conductors, preferably although not necessarily having high resistance, said conductors crossing each other in a close-knit configuration. The conductors are "printed" on opposite sides of an insulating sheet 43 whereby they do not touch at the crossing points. The parallel conductors are connected at their ends so as to constitute at least one continuous trigger circuit.

In FIG. 1 there is shown a total of four continuous trigger circuits formed by the crisscross conductors of the grid 42. To effect this, the grid is formed to have on one side of the sheet 43 a zigzag configuration comprising a pair of spaced-apart conductors 44, 46 and to have the other side of the sheet 43 a similar zigzag configuration comprising a pair of spaced-apart conductors 48, 50. Preferably, as shown, the conductors 44, 46 extend at right angles to the conductors 48, 50.

A pair of leads is brought from each of these continuous trigger circuits. As shown, lead wires 52, 54 constitute one such pair of leads; lead wires 56, 58 constitute a second pair of such leads; lead wires 60, 62 constitute a third pair of leads; and lead wires 64, 66 constitute the fourth pair of leads. The pairs of lead wires are preferably brought from the grid configuration 42 in cable, this latter being indicated by the numeral 68 designating a broken outline.

Each pair of lead wires is connected to a different leg of the bridge 20, in series with the leg. Thus, the wires 52, 54 are connected respectively to terminals A, B in the bridge leg having the resistor 22. The lead wires 56, 58 are connected respectively to terminals C, D in the leg containing the resistor 24 of the bridge; the lead wires 60, 62 are connected respectively to the terminals E, F in the leg containing the resistor 26 of the bridge; and the lead wires 64, 66 are connected to the terminals G and H in the leg containing the resistor 28 of the bridge.

As a consequence, the four legs of the bridge respectively contain the four continuous trigger circuits of the grid formation 42. The formation 42 may be substantially flat or planar, whereby it can constitute part (one side, for example) of a restricted or security enclosure. The grid 42 may, for instance,

comprise the single otherwise vulnerable wall of an enclosure whose other walls are especially impregnable. Or, the grid 42 may be considered symbolic, representing all six walls of an enclosure such as a vault, strongbox or the like, this being depicted in FIGS. 9 and 10. FIG. 9 depicts a walk-in vault, whereas the showing of FIG. 10 is that of strongbox or safe. In each of these instances, the six confining surfaces or formations may be each constituted of a flat grid configuration similar to that indicated at 42 in FIG. 1. Four of the grid formations may be paired whereby there are two pairs, with the trigger circuits in each pair being series connected. The remaining two individual grid formations may be independent of each other, whereby the result is a total of four separate trigger circuits for connection to the four legs of the bridge 20. Appropriate selection of grid conductor resistances can be made, to provide for approximate equalization of the resistances of the four trigger circuits.

In the grid configuration 42 of FIG. 1 the conductor 44 forms one continuous trigger circuit, the conductor 46 forms a second continuous trigger circuit, the conductor 48 forms the third continuous trigger circuit and the conductor 50 forms the fourth continuous trigger circuit.

It will be understood that the grid configuration 42 may constitute, for example, the front door panel 70 of the strongbox 72 shown in FIG. 10, or it may constitute the top or ceiling panel 74 of the vault 76 illustrated in FIG. 9. Or, the grid configuration 42 in FIG. 1 may be representative of an enclosure for all six sides of the strongbox 72 or vault 76. In FIG. 9 the detector station is indicated at 78, and in FIG. 10 it is indicated at 80. Such detector stations may contain the bridge circuit 20 shown in FIG. 1. The cable 68 of FIG. 1 is given a similar character in FIGS. 9 and 10.

With the above circuit organization the bridge is placed in balance by appropriate adjustment of the variable resistors 22, 24, 26 and 28. When the bridge is in adjustment, a null indication will be given on the instrument or galvanometer 40. Upon the system being thus balanced, any change in the characteristics of the printed-conductor trigger circuits of the grid 42 will cause an unbalance of the bridge whereupon the instrument 40 will immediately indicate such unbalance signifying that some alteration of the grid protective system has occurred, presumably as a result of tampering or efforts to penetrate the restricted space.

From the foregoing it can be seen that we have provided a novel and improved area security apparatus wherein any tampering whatsoever with the conductors of the grid configuration, causing a severance of such conductors or a shorting of one conductor to another will result in the tampering being made known.

A more sophisticated detection circuit for connection to the printed-conductor trigger circuits of the grid 42, is illustrated in FIG. 7. In this figure, the terminals A, B, C, D, E, F, G and H may be connected respectively to the lead wires 52, 54, 56, 58, 60, 62, 64 and 66 which are shown in FIG. 1 as being connected to the terminals of the bridge 20 having the above letters A through H. In other words, the circuitry shown in FIG. 7 is to be substituted for the bridge circuit 20 of FIG. 1, in its entirety.

In FIG. 7, the variable resistors of the four legs are designated respectively 22a, 24a, 26a and 28a. The corner junctions of the bridge are designated respectively 30a, 32a, 34a, and 36a. The juncutres 30a, 34a are connected to the terminals of a galvanometer 40a, and the juncutres 32a, 36a are connected respectively by wires 82, 84 to a battery 38a, the wire 84 including an on-off switch 86. Accordingly, the bridge is energized from the battery 38a and may be placed in balance by suitable adjustment of the adjustable resistors, as with the case of the bridge 20 of FIG. 1.

The galvanometer-type instrument 40a controls a movable shutter 88 having an aperture 90 in it. Adjacent the movable shutter 88 is an incandescent electric lamp 92 connected by wires 94 and 96 and a resistor 98 to the battery 38a. Closing of the switch 86 will accordingly effect illumination of the lamp 104.

In conjunction with the galvanometer 40a, lamp 92 and movable shutter 88 there is provided a phototransistor or light sensitive cell of the transistor-type, having a base 100, collector 102 and an emitter 104. The base 100 is connected through a resistor 106 and wire 108 with the positive supply wire 96 from the battery 38a. The emitter 104 is connected by a wire 110 to the bridge juncture 36a which has a connection with the positive supply wire 84 of the battery 38a. The emitter 104 is also connected by a wire 114 to a relay coil 116 which is in turn connected to an emitter 118 of a power transistor 120 whose base 122 is connected by wire 124 to the collector 102 of the light sensitive cell 105. A resistor 126 connects the base 122 of the power transistor 120 to the wire 114, said base being also connected through a resistor 128 and wire 130 to the collector 132 of the transistor 120. The wire 130 is also connected to the bridge juncture 32a which goes to the negative supply line from the battery 38a. The relay coil 116 controls movable contacts 134 and 136, the latter being a holding contact engageable with a stationary contact 138 connected to the transistor emitter 118. The movable contact 136 is connected through a switch 140 to the collector 132.

The movable relay contact 134 connects through a wire 142 with a battery 144 which is connected to a switch 146 for controlling a signal or bell 148. The bell 148 is connected by a wire 150 to the stationary contact 152 which is cooperable with the relay contact 134.

As distinguished from the signal 148, a circuit control may be affected by connecting the wires 142 and 150 to a relay coil 154 and battery 156. Circuit-opening contacts 158 are actuated by the coil 154, and may be used to open any desired circuit.

Operation of the circuit of FIG. 7 is as follows: With the bridge balanced by suitable adjustment of the resistors 22a, 24a, 26a, and 28a, the shutter 88 will be centralized, and light from the lamp 92 will strike the light sensitive cell 105. This effects a conductive path between the collector and emitter 102, 104 of the cell 105, thereby effecting a clamping action between the base 122 and emitter 118 of the transistor 120. In other words, the effect of light striking the cell 105 is such that no appreciable voltage or potential difference exists between the base 122 and emitter 118 of the power transistor 120. In other words, the effect of light striking the cell 105 is such that no appreciable voltage or potential difference exists between the base 122 and emitter 118 of the power transistor 120. However, when the shutter 100 deflects to one side or the other, light will be shut off from the phototransistor 105, terminating the conductive path between the collector and emitter 102, 104. The clamping action thus ceases, and voltage can now exist across the resistor 126, meaning that a potential will exist between the base 122 and the collector 118 of the power transistor 120. Such voltage will render the transistor 120 conducting whereby the relay coil 116 will be energized by current flowing through the collector and emitter. The result of this is that the relay coil 116, being energized, will actuate the relay contacts 134, 136. The relay contact 136 is in the nature of a holding contact, and will maintain the relay energized regardless of shutting off of the transistor 120. The relay contacts 134, 152 will effect energization of the bell 148 and actuation of the control 144, sounding an alarm and indicating that the bridge has been unbalanced, as by alteration of the printed conductors, ostensibly from tampering with the grid 42.

Another embodiment of the invention is illustrated in FIG. 8. Here there is shown a bridge 20b having variable resistors 22b, 24b, 26b and 28b in its four legs. The opposite corner juncutres 30b, 34b of the bridge are connected with an indicating instrument 40b, and the corner juncutres 32b, 36b are connected with a battery 38b. One leg of the bridge is broken and connected to terminals G, H which are connected by a cable 68b with terminals I, J of a grid configuration 42b. The grid configuration 42b comprises but a single continuous trigger circuit comprising the conductors on both sides of the insulating sheet 43b, said circuit having its two ends connected 75 with the terminals I, J as shown. Thus, the grid 42b is in only

one leg of the bridge 20b. When the bridge has been balanced, any alteration of the characteristic or resistance of the grid configuration 42b will result in an unbalance, shifting the galvanometer 40b from its null position and indicating the abnormal condition. Such abnormal condition could be either a break in the conductor of the grid 42b, or else a short circuit condition between any two or more conductors of the grid.

The grid configuration 42 of FIG. 1 or 42b of FIG. 8 is as already stated, preferably in the nature of printed circuitry, shown in cross section in FIGS. 2 and 3. The grid configuration may be applied to wall paper or to wall panels. For example, in FIG. 4 the grid configuration 42 is applied to one side of wall paper 162. Or, the grid 42 may be applied to one side of a plywood panel 164 as shown in FIG. 5, or to one side of a plasterboard panel 166, as shown in FIG. 6.

In place of the detector bridge circuits of FIGS. 1, 7 and 8, a simpler detector circuit may be utilized for connection to the grid configuration, as indicated in FIG. 15. In this figure, the terminals I and J correspond to the like lettered terminals of the grid configuration 42b shown in FIG. 8. These terminals are connected by means of a cable 68c to terminals K and L of a detector circuit comprising a microammeter or current indicating device 168 connected in series with a variable resistor 170 and battery 172. This series circuit is connected to the terminals K and L, and the resistor 170 is adjusted to give a normal reading on the instrument 168. Any alteration of the characteristics of the grid 42b connected to the terminals I and J will result in deflection of the instrument 168 away from its norm, whereby an indication will be had of tampering or other unusual condition involving the grid and the restricted area which it surrounds.

The printed circuit grid 42 may be extremely flexible and rugged whereby it could be applied to one side of fabric. Thus, a bag or canvas such as that indicated at 176 in FIG. 14 could be provided with the grid, which is connected through a separable connector fitting 178 and cable 68 to a detector circuit unit 180 containing a bridgelike 20. The bag 176 could be anchored to the floor surface by a suitable clamp 182. Any disturbance of the trigger circuitry will cause an indication to be given at the remote station 180.

The cable 68 may be constituted generally as shown in FIG. 13, comprising a signal wire core 184 and inner and outer insulated resistance-wire braids 186 and 188 respectively. The braid wires may be connected so as to be included in the trigger circuits of the guard equipment, in series with the conductors of the grid 42. Details of the cable 68 are given in the above-identified copending application, Ser. No. 755,203.

FIGS. 11 and 12 illustrate an electrical junction box 190 which is guarded by a grid 42 lining its walls and cover. The box 190 has cables 68 connected to it. The braids of the cables are connected to the conductors of the grid 42 by plug-and-socket fittings 192 whereby continuity of the trigger circuits is had. One of the cables 68 in FIGS. 11 and 12 has its braid wires connected to a detector bridge such as the bridge 20 shown in FIG. 1. Thus, any disturbance of the grid 42 in the junction box 190 will be immediately detected in the manner already described above.

It will now be understood from the foregoing that we have provided a novel and improved guard apparatus which is responsive to violation of a security space or area, as occasioned by any alteration in the characteristics of the printed circuit grid placed around such area. The possibility of penetration of the grid being effected without altering its electrical characteristics and indicating such condition is extremely remote and unlikely. The guard apparatus as above set forth is seen to be relatively simple, sensitive in response and foolproof in operation. Relatively low voltages and currents are involved, which may be readily supplied by batteries, thereby eliminating hazard to authorized personnel in the area, and also eliminating dependence on commercial power sources. The apparatus is of relatively low cost, and the grid configurations readily adapt themselves to various constructional requirements, being easily incorporated in building panels, or being applied to existing building structures.

Variations and modifications are possible, and portions of the improvement may be used without others.

We claim:

- 1 An area security apparatus comprising, in combination:
  - a. a grid constituted of conductors insulated from and crossing each other in a close-knit configuration,
  - b. said conductors being connected at their ends to constitute at least one continuous trigger circuit,
  - c. at least one pair of leads connected with said continuous circuit,
  - d. said grid being shaped to constitute at least part of an enclosure in which objects which are to be protected are disposed,
  - e. an electrical detection circuit having at least two terminals connected to said pair of leads,
  - f. means providing electrical energy in said detection circuit,
  - g. said detection circuit including an electroresponsive device responding to the characteristics of the trigger circuit, thereby to register any alteration of said characteristics,
  - h. said grid comprising a planar printed-circuit configuration having a rigid insulating sheet and sets of conductors printed on both sides of said sheet, extending in different directions.
2. An apparatus as in claim 1 wherein:
  - a. the grid comprises four independent circuits,
  - b. said detection circuit comprising an electrical bridge,
  - c. said four independent circuits of the wire mesh being connected respectively in the four legs of the bridge.
3. An apparatus as in claim 2, wherein:
  - a. two of the independent circuits of the grid comprise conductors on one side of the sheet,
  - b. the remaining two of the independent circuits of the grid comprising conductors on the other side of the sheet.
4. An apparatus as in claim 1, wherein:
  - a. the grid comprises a single continuous circuit constituted of insulated sets of conductors disposed on opposite sides of the insulating sheet.
